DAVID SOLOMON ELLIS, OF SYDNEY, AND FREDERICK WILLIAM TIDD, OF ROCKDALE,
NEAR SYDNEY, NEW SOUTH WALES, AUSTRALIA.

MOP AND WRINGER COMBINED.

1,200,929.

Specification of Letters Patent. Patented Oct. 10, 1916.

Application filed April 6, 1916. Serial No. 89,406.

To all whom it may concern:

Be it known that we, DAVID SOLOMON ELLIS and FREDERICK WILLIAM TIDD, citizens of the Commonwealth of Australia, residing at, 5 as to the former, 204 Clarence street, Sydney, in the State of New South Wales, Commonwealth of Australia, and, as to the latter, Rockdale, near Sydney, in the State and Commonwealth aforesaid, have invented 10 certain new and useful Improvements in Mops and Wringers Combined, of which the following is a specification.

This invention relates to a simple mop appliance in which the cloths or swabs are 15 detachably associated with a pair of T shaped frames, one of which is securely attached to the bottom end of the mop-handle, so as to form the pressure head piece; for both holding and operating the cloth, while 20 the other frame—attached to a tubular part—is carried upon the handle above the head piece, so that it may both slide and be rotated thereon, and while serving the purpose of a secondary holder for the cloth, 25 also provides an efficient means for wringing it, if it be a wet or moistened cloth.

By exchanging one cloth for another the appliance may be utilized for other purposes than as a mop only, that is to say, after a 30 cloth or swab suitable for wetting, cleaning, and drying, has been used upon a floor or other surface, another may be substituted which is suitable for polishing, this may also be displaced by another suitable for 35 sweeping and dusting, and so on. Whatever be the texture of cloth or swab which may be utilized, the same mode of securing or attaching it to the frames may be employed which consists in the use of a perforated slat laid upon and secured transversely to each end of the cloth.

In the accompanying drawings:—Figure 1—is a perspective view of the mop cloth, or swab, with transverse securing slats attached 45 thereto. Fig. 2—is a plan of the T shaped head and pressure piece with slidable hook thereon, also securing tube on handle. Fig. 3—is a plan of the T shaped secondary holder and wringer frame. Fig. 4—is a plan of the mop appliance showing the various parts assembled, and with cloth attached 50 fully extended. Fig. 5—is a side elevation of Fig. 4. Fig. 6—is a sectional elevation showing detail of the handle with leg parts 55 of head piece fitted therein, and surrounded

with securing tubes. Fig. 6^A—is detail showing fragment of handle with leg pieces in grooves. Fig. 7—is a sectional elevation showing detail of wringer tube and frame parts secured therein. Fig. 8—is a perspective view of the slidable hook—enlarged. Fig. 9—is a side elevation of the mop with the cloth in a folded forward position, as when in operation. Fig. 10—is a side elevation similar to Fig. 9, but with the cloth in 65 a folded rearward position. Fig. 11—is a plan of the mop showing the wringing action obtained by rotating the wringer frame.

To simplify and cheapen the construction of the appliance the drawings have 70 been made to indicate a skeleton frame formation such as would be shaped when wire is used for the purpose, but these parts may if desired be made in the form of castings 75 and drop forgings, but the general characteristics which appear in the different figures would be essentially the same.

An ordinary kind of mop handle A is 80 suitable for use with this invention, and is provided with the side grooves or sinkages 80 A¹ Figs. 6 and 6^A to receive the leg pieces B¹ 85 which are made continuations of the loop-shaped head piece B and are kept flush circumferentially and have their curved ends B² driven or pressed into the handle, to retain them in a central position, and are inclosed with the tightly fitting metal tube C. The legs are parallel so as to serve as a reel upon which the cloth may be tightly wound when the wringer is rotated. The slidable 90 hook D, running freely on the legs may be used to prevent the displacement of the cloth when placed in the loop head piece. The wringer is somewhat similarly shaped to the fixed head piece, its looped shaped 95 holder part E being similar to the piece B, the legs E¹ being also continuations, but these are arranged diagonally to provide sufficient clearance for rotating it around the handle Figs. 5 and 11, and are downwardly directed as in Figs. 5, 9 and 10, to give transverse clearance for the cloth slat. They are secured in the tubular metal slide E², whose side tubes E³ are adapted to fit them. These side tubes are shown in Fig. 7 100 in a position below the center of the handle A, such location being serviceable for downwardly directing the legs E¹ so as to give the desired clearance.

The cloth or swab F Fig. 1 which is made 110

of any material suitable for the purposes indicated, is preferably rectangular in shape, and has the slats G attached transversely at each end. These have piercings G¹ through which cord or wire stitching G² is passed through the cloth. The slats are of a sufficient width and length to take a seating upon the looped parts B and E, and are simply pushed through the loops end-wise, and when turned on the flat with the stitched parts of the cloth pushed slightly on one side a full bearing may be obtained upon the metal frames. A small side margin F¹ is allowed on the cloth beyond the ends of the slats to prevent the metal parts coming in contact with the floor surface. The sliding hook D may be placed in the position indicated in Figs. 2, 4 and 5 it being pushed under the cloth and over the looped holder B.

When in use the cloth or swab occupies a folded position so that half of the surface is utilized at a time. Figs. 9 and 10 illustrate its use on both surfaces, whether such surfaces are in a wet or dry condition or when used for polishing.

The wringing operation is performed by simply grasping the handle A, with one hand, and the tubular slide E² to which the wringing member is attached, with the other hand, and by rotating it the swab F is wound around the parallel legs B¹ producing the result indicated in Fig. 11.

Having now described our invention what we claim as new and desire to secure by Letters Patent is:—

1. In a mop and wringer combined, the combination with a handle, of a fixedly at-

tached pressure head piece of looped formation and provided with spaced parallel legs 40 connecting the fixed head piece to the handle, a mop cloth connected with the pressure head piece, and means having connection with one end of the cloth for winding the latter about said legs as described. 45

2. In a mop and wringer combined, the combination with a handle, of a fixed pressure head piece of looped formation and provided with spaced parallel legs connecting the fixed head piece to the handle, and 50 a wringing member consisting of a tubular slide rotatably and slidably mounted on the handle, and a looped shaped holder member supported by said tubular slide and capable of being rotated around the fixed 55 parallel legs, and a mop cloth connecting the pressure head piece and the wringer member.

3. In a mop and wringer combined consisting of a fixed head piece attached to the 60 mop handle, and a slidably rotatable wringing member located on said handle above such head piece, a detachable cloth or swab consisting of a rectangularly shaped cloth, 65 transverse slats secured at each end of said cloth and adapted to fit the said fixed and rotatable members as described, and illustrated and for the purposes set forth.

In testimony whereof, we have signed our names to this specification in the presence 70 of two subscribing witnesses.

DAVID SOLOMON ELLIS.
FREDERICK WILLIAM TIDD.
